UNITED STATES PATENT OFFICE.

FRANK G. CALDWELL, OF WHEELING, WEST VIRGINIA.

CEILING-PANEL.

SPECIFICATION forming part of Letters Patent No. 440,008, dated November 4, 1890.

Application filed July 8, 1890. Serial No. 358,077. (No model.)

To all whom it may concern:

Be it known that I, FRANK G. CALDWELL, a citizen of the United States, residing at Wheeling, in the county of Ohio and State of 5 West Virginia, have invented new and useful Improvements in Ceiling-Panels, of which the following is a specification.

This invention relates to the metallic ceiling-panels described and shown in the Letters Patent issued to me August 27, 1889, No. 409,916, and October 29, 1889, No. 414,017.

The objects of my present invention are to improve the prior construction, to provide a ceiling-panel comprising an open wooden frame and a metal sheet, whereby the panels will so overlap each other that two edges of the metal sheet of one panel can be nailed to the edges of the open frames of adjoining panels, and thereby present an unbroken surface, and 15 finally to provide novel means whereby the open wooden frame of one panel can be nailed at two edges to the rafters or similar supports and the projecting metallic edges of the adjoining panels can be extended over and 20 serve to conceal the nails or other fastenings employed to attach such edges of the open wooden frame.

To accomplish all these objects my invention involves the features of construction 30 and the combination or arrangement of elements hereinafter described and claimed, reference being made to the accompanying drawings, in which—

Figure 1 is a plan view on a reduced scale, 35 showing several panels in position as when applied to constitute a ceiling. Fig. 2 is a detail perspective view showing one of the panels on a larger scale. Fig. 3 is a similar view showing the metal sheet corrugated. 40 Fig. 4 is a transverse sectional view of the panel, comprising a plain metal sheet stretched on the wooden frame.

In the accompanying drawings, exhibiting 45 my invention, the numeral 1 indicates an open wooden frame, which, as shown, is approximately square, but may be otherwise shaped in outline. This frame is rigid and comprises wooden bars properly joined at

their ends by suitable joints—such as miters or tongues and grooves—and to one surface 50 of the frame is attached by nails or other fastenings 2 the metal sheet 3, which is tightly drawn or stretched. The metal sheet is so disposed on the wooden frame as to project therefrom at two edges to form overhanging 55 flanges 4 and 5, running at right angles to each other if the frame is square or rectangular. By this arrangement the wooden frame projects at two edges to form supporting-ledges 6 and 7, which extend, respectively, parallel 60 with the overhanging flanges of the metal sheet. In applying the panels to form a ceiling or similar surface they are placed, as indicated in Fig. 1, in such manner that the overhanging flanges of a metal sheet overlie 65 the ledges of two adjoining or adjacent panels, and such flanges are nailed or otherwise secured to such ledges, as at 8, in such manner as to form practically an unbroken metallic surface. 70

In Figs. 1, 2, and 4 the metal sheet is shown plain or non-corrugated, and the overlying flanges are rigid, while in Fig. 3 the metal is corrugated. The metal sheets are comparatively thin; but the wooden frame imparts the 75 required stiffness, rigidity, strength, and durability to the panel as a whole, while rendering it possible to provide light and easily handled panels, which can be rapidly assembled to produce a ceiling or like surface. The exposed ledges of the wooden frame serve to nail or similarly attach the panels to the rafters or other overhead work or supports without perforating the metal sheets for the panel-attaching nails, and obviously the overhanging 80 flanges of the metal sheets overlie and cover and conceal the nails or fastenings which pass through the exposed parts or ledges of the open wooden frames. The attachment of the metal sheet to one surface of the open wooden 85 frame avoids the recess formed by the wooden frame in the exposed surface of the panel, as in my Letters Patent alluded to, and the whole provides a useful and desirable structure for obtaining practically unbroken ceiling-surfaces. 90 95

Having thus described my invention, what I claim is—

As an improved article of manufacture, a ceiling-panel consisting of a rigid wooden frame and an attached metal sheet having edges projecting to form overhanging flanges, and other edges terminating to leave the open wooden frame projecting as ledges to attach

the panel and also serve as supports for adjacent panels, substantially as described. 10

In testimony whereof I have affixed my signature in presence of two witnesses.

FRANK G. CALDWELL.
